UNITED STATES PATENT OFFICE.

GEORGE D. SAILER, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A LIQUID-DISPENSER.

58,110.

Specification for Design.

Patented June 7, 1921.

Application filed July 10, 1920. Serial No. 395,398. Term of patent 14 years.

To all whom it may concern:

Be it known that I, GEORGE D. SAILER, a citizen of the United States, residing at Jeannette, in the county of Westmoreland, State of Pennsylvania, have invented a new, original, and ornamental Design for Liquid-Dispensers, of which the following is a specification, reference being had to the accompanying drawing, forming part thereof.

The figure is a perspective view of a liquid dispenser showing my new design.

I claim:

The ornamental design for a liquid dispenser, as shown.

GEORGE D. SAILER.
